UNITED STATES PATENT OFFICE.

JOHN W. DUVAL, OF PITTSBURGH, PENNSYLVANIA.

ADVERTISING MACHINE.

1,420,627.

Specification of Letters Patent. Patented June 27, 1922.

Application filed April 16, 1920, Serial No. 374,422. Renewed April 13, 1921. Serial No. 461,149.

To all whom it may concern:

Be it known that I, JOHN W. DUVAL, a citizen of the United States, residing at Pittsburgh, in the county of Allegheny and 5 State of Pennsylvania, have invented new and useful Improvements in Advertising Machines, of which the following is a specification.

This invention relates to advertising machines and has for an object the provision of a machine in which a number of advertisements are consecutively and automatically brought into view, novel means being provided for the accomplishment of this 10 purpose. Another object is the provision of an advertising machine in which the display matter is carried by a number of curtains, means being provided for bringing the curtains into position in regular order and unrolling them in the manner to present the advertising matter thereof to view.

Another object of the invention is the provision of means for illuminating the advertisement when the latter is brought fully 15 into view, said illumination being extinguished after a predetermined period, so that the intermediate intermittent operation of the illuminating mechanism will serve to attract attention to the advertising matter 20 displayed.

Another object is the provision of a plurality of directory or information sheets or curtains, which may be operated in conjunction with the advertisement to attract attention to the machine, the sheets or curtains 25 being adapted to be brought into view for inspection when desired.

Another object is the provision of novel 30 means for selecting the particular information sheet or curtain, so that a person desiring certain information may set the machine and release its operating mechanism, whereupon the sheet or curtain selected will be automatically brought into view.

Other objects and advantages of the invention will appear as the following description is read in connection with the accompanying drawings.

In the drawings:

50 Figure 1 is a front elevation of the invention.

Figure 2 is a side elevation of the same.

Figure 3 is a section taken approximately

on the line 3—3 of Figure 2 and looking in the direction of the arrow. 55

Figure 4 is a skeleton view showing in front elevation the frame work of the machine and certain of the operating mechanisms.

Figure 5 is a side elevation of the subject 60 matter of Figure 4.

Figure 6 is a sectional view taken horizontally through the machine at a point approximately on the line 6—6 of Figure 1.

Figure 7 is a sectional view on the line 65 7—7 of Figure 6.

Figure 8 is a similar view on the line 8—8 of Figure 6.

Figure 9 is a like view on the line 9—9 of Figure 6. 70

Figure 10 is a fragmentary sectional elevation showing the information sheets or curtains and the selective mechanism therefor.

Figure 11 is a horizontal sectional view on 75 the line 11—11 of Figure 10.

Figure 12 is a section on the line 12—12 of Figure 10.

Figure 13 is a horizontal sectional view 80 through the upper portion of the cabinet and showing the advertising sheets or curtains in plan.

Figure 14 is a fragmentary front elevation of the mechanism shown in Figure 13.

Figure 15 is an end view of the same. 85

Figure 16 is a fragmentary plan view of the reversing mechanism used in connection with the advertising sheets or curtains.

Figure 17 is a front elevation of the same.

Figure 18 is a fragmentary elevation of 90 the selective mechanism for the information sheets or rolls.

Figure 19 is a section on the line 19—19 of Figure 18.

Figure 20 is a similar view on the line 95 20—20 of Figure 18.

Figure 21 is a fragmentary elevation looking at one end of the mechanism shown in Figure 20.

Figure 22 is a fragmentary view of the 100 clutch and its operating mechanism used in the selective mechanism for the information sheets or curtains.

Figure 23 is an end view showing the locking mechanism. 105

Figure 24 is a fragmentary elevation of the

curtain chain and the sheets or curtains carried thereby.

Figure 25 is a view at right angles to Figure 24.

5 Figure 26 is an end view of the mechanism shown in Figure 24.

Figure 27 is a similar view looking at the opposite end of the mechanism shown in Figure 24.

10 Figure 28 is an enlarged view of the cam used in the advertising mechanism.

Figure 29 is a similar view of the cam used in the information mechanism.

15 Figure 30 is a diagrammatic view showing the contacts and circuits for lighting the lamps which illuminate the advertising sheets or curtains during the pause of the carrying plate at each operation of the advertising mechanism.

20 Figures 31 and 32 are detailed perspective views of the chain carried bracket links.

While the invention is herein shown and described as an advertising device, it will be apparent from an understanding of the 25 same, that it is susceptible of various other uses and it is not the purpose of the present application to limit the invention to this use. For a clear understanding of the invention however, certain of the mechanism will be 30 hereinafter referred to as the advertising mechanism and certain other parts of the mechanism hereinafter referred to as the directory or information mechanism.

In carrying out the invention there is provided a cabinet which is indicated at 18, the front of the cabinet being provided near the center and at one side with an opening which is covered by a glass panel 19 to provide a display opening for the information sheets 35 or curtains to be hereinafter described. The top of the cabinet is also provided with an opening, which is covered by a glass panel 20 to provide a display opening for the advertising sheets or curtains, also to be hereinafter described. The lower portion of the cabinet is provided with doors 21, by means 40 of which access may be had to the interior, while the top of the cabinet is provided with a hinged cover or closure 22 for a like purpose. The cabinet 18, reduces in width at its central point, so that a table or shelf 23 is provided, the latter forming a support for an index 23^a, around which moves a pointer 23^b which is controlled by a hand wheel 24. 45 Extending through the table or shelf 23, is an operating knob 25, both this knob and the hand wheel 24 controlling the operation of the information mechanism, as will be hereinafter apparent.

50 Located within the cabinet and secured to the base thereof, is a suitable motor 26, the shaft of the motor carrying a pinion 27, which operates a main drive shaft 28, through the medium of a gear 29. The shaft 55 28 is mounted in suitable bearings 30 secured

to the base of the cabinet and has secured thereon a gear 31, having a relatively wide face. Meshing with the gear 31, is a gear 32 the latter being loose upon a counter shaft 33, which is mounted for rotation in bearings 34 also secured to the base of the cabinet. 70 Each side of the gear 32 is provided with an extended hub, the outer end of which is formed with a clutch face, one of which is adapted to engage a clutch member 46 fast upon the shaft 33 and the other a clutch face formed on a bevel pinion 55 which is rotatable upon the shaft 33. A similar pinion 47 is fast upon the shaft 33 and both the pinions 55 and 47 are adapted 75 to engage a bevel gear 48 which is secured upon a vertically disposed shaft 49, the latter extending through the height of the cabinet and carrying at its upper end spaced sprocket wheels 50. The sprocket wheels 50 are fast upon the shaft 49 and passing over these sprockets are lower and upper chains 51 and 51^a respectively, these chains also passing around idle sprockets 52, mounted upon short vertically disposed shafts 52^a 80 having bearings in the frame work of the cabinet. 85

Also secured upon the shaft 28 is a pinion 35, the latter driving a gear 36, which is mounted on a short shaft 37, which rotates 95 in bearings 38. The shaft 37 is further provided with a pinion 39 which drives a gear 40. This gear is mounted upon a short shaft 41, which operates in bearings 42. The shaft 41 also has mounted thereon a collar 43 which is provided with a cam groove 43^a and operating in the groove is a roller 43^b, which is mounted upon one end 100 of a lever 44. This lever is pivoted at 45 upon the base of the cabinet and its opposite end is connected to one of the hubs of the gear 33 as indicated at 45^a.

From the foregoing description it will be seen that rotation of the collar 43 through the reduction gears just described will, 110 through the cam groove 43^a rock the lever 44 upon its pivot to shift the gear 32 to engage either the clutch member 46, or the clutch member upon the bevel pinion 55. This regulates the direction of rotation of 115 the sprocket wheels 50 and reverses the direction of travel of the chains 51 and 51^a, which pass over said sprockets, by shifting the lever 44 in opposite directions, so as to regulate the direction of rotation of the 120 shaft 49 and cause the chains to alternately travel in opposite directions.

125 Mounted within the upper end of the cabinet is a plurality of centrally disposed shafts 74, 75 and 76, the shaft 74 and the shaft 49 having loosely mounted thereon sprockets 72. Passing over these sprockets are chains 64 and chains 64^a, which are spaced apart to provide lower and upper chains respectively, a pair of these chains 130

being mounted at each end of the display opening or panel 20. These chains are driven by a sprocket 72 and pass over sprockets 73 which are mounted upon the 5 shafts 75 and 76.

Each of the chains 64 and 64^a comprise bracket links 65 and 65^a, these links alternating with the usual chain links and being connected by rods 70, which extend from 10 the links of the chain 64 to the chain 64^a. The bracket links 65 are each provided with a circular opening 66, while the bracket links 65^a of the chain 64^a are provided with notches 69, so as to provide for mounting 15 between the links of the upper chain 64^a and the lower chain 64, a plurality of spring controlled sheets or curtains 67 as shown in Figures 24 and 25 of the drawings. These sheets or curtains are provided along 20 their outer edges with rods 68, which project beyond the chains and when the sheets or curtains are rolled, are adapted to engage hooks 68^a provided in the ends of the bracket links.

25 Through the mechanism just described these sheets or curtains are adapted to be consecutively brought into position at opposite ends of the display opening and to rest or pause in such position for a predetermined period whereupon, the sheets or curtains are unrolled over the display opening. To accomplish this there is provided 30 a carrying plate 53, the latter being secured at the opposite ends of the chains 51 and 51^a 35 and to be moved backward and forward across the display opening by the operation of the chains as previously described. For the purpose of engaging the sheets or curtains, the carrying plate 53 is provided adjacent each end with oppositely extending 40 hooks 53^a, these hooks being adapted to engage the projecting ends of the rods 68 and to unwind the curtain of the rod so engaged and carry the latter across the display opening. When the carrying plate 53 reaches the opposite side of the opening and 45 starts upon its reverse movement, the opposite hooks 53^a will engage the end of the rods 68 upon that end of the opening and 50 carry its curtain across the said opening upon the reverse movement of the plate. When the plate again reaches the end of its travel, the first curtain will be released 55 and the chains 64 and 64^a operated to position another sheet or curtain in the path of the hooks 53^a.

To accomplish the movement of the curtains or sheets, there is provided a lever 79 which is pivoted as at 80 and carries a pawl 78. This pawl engages a ratchet 73 mounted upon a shaft 76, this mechanism being duplicated at each end of the display opening. Prior to the end of travel of plate 53 the latter engages the free end of the lever 65 79, so as to move the sprocket 73 a distance

of one tooth, this movement being sufficient to bring the next advertising sheet or curtain into position for engagement with the hooks of the plate 53. The movement of the lever 79 is resisted by a spring 82, while 70 a stop 81 serves to limit the movement of the lever in one direction.

Carried by the sprocket chain 51, is a lug 56 the latter being adapted to engage lugs 57 positioned at each end of a bar 58. This 75 bar is slidably mounted in bearings 59 secured to the frame and has secured thereon a pair of spaced collars 60. When the chain 51 reaches the end of its movement, the lug 56 will engage one of the lugs 57 to cause one 80 of the collars 60 to move into engagement with the lever 61, which is secured to a shaft 62. This shaft is provided with a lug or finger 63 which engages a groove in the hub of the gear 32, shifting the said gear to a 85 neutral position between the clutch member 46 and the clutch member of the beveled pinion 55, thereby, causing a pause or tarry in the operation of the mechanism and leaving the sheets or curtains at rest before the 90 display opening for a predetermined length of time, or until the operation of the shifting levers 44 moves the gear 32 into engagement with one of the clutch members.

The main power shaft 28 also has secured 95 thereon a gear 83, which engages a gear 84, loosely mounted upon a counter shaft 85 the latter operating in bearings 86 secured to the base of the cabinet. The gear 84 is provided upon each face with an extended hub, to provide a ratchet member, the latter being adapted to engage a ratchet member formed on the hub of a bevel gear 146 which is loose on the shaft 85 and a ratchet member 150 fast upon said shaft. 100 105

A hand wheel 24 is secured upon the upper end of a short vertical shaft 87, which is operated in bearings carried by the frame and at the lower end of the shaft 87 is a beveled gear 88. This gear engages a bevel 110 gear 89, which is provided at its rear with an extended hub 89^a and extending from the opposite face of this gear is a sleeve 89^b. This sleeve has secured upon its outer end a drum 89^c, which carries a segmental lug 90. 115 The gear 89 is mounted upon the shaft 96, which is mounted in bearing 91 located within the cabinet. A ratchet wheel 92 is secured to the shaft 87 of the hand wheel, the said ratchet being engaged by a dog 93, 120 which is pivotally mounted as indicated at 94 and is held in yielding engagement with the teeth of the ratchet wheel 92 by means of spring 95. The shaft 96 carries at one end a collar 97 which is fast thereon and secured to this collar is one end of a coil spring, the opposite end of this spring being secured to the hub of the bevel gear 89 which is loose upon the shaft. Mounted upon the shaft 96 is a gear 99, one face of 130

which carries a segmental lug 100, which is adapted to engage the lug 90 of the drum 89. The gear 99 meshes with the pinion 101, which is secured to the shaft 102, the latter being operated in bearing 103. The shaft 102 also has secured thereon sprocket wheels 104, over which operate chains 105 and 105^a, similar in construction to 64 and 64^a described in connection with the advertising mechanism. The chains 105 and 105^a are adapted to carry sheets or curtains 200, which are adapted to have imprinted thereon suitable indicia, for example, sections of a business or city directory. These sheets 15 or curtains may be alphabetically arranged and the index 23^a upon the table or shelf 23 may correspond to the arrangement of the information sheets or rolls 200. Thus, if it is desired to ascertain the location of a 20 person or building, the particular letter under which the person or building would be classified, would be the point at which the indicator is adjusted for the operation of the information mechanism, so as to cause 25 the particular sheet selected to appear before the display panel 19, as will be hereinafter apparent.

The chains 105 and 105^a pass over idle sprocket wheels 107, which are mounted 30 upon shafts 108 and as before stated, these chains carry the spring controlled information sheets or curtains 200, which are similar to the sheets or curtains 67 and like these sheets or curtains carry rods 201. These 35 rods are engaged by hooks secured to a carrying plate 109, the said plate being similar to the plate 53, except that the rod engaging hooks 202 are located only along the bottom edge of the plate: and while the 40 plate 53 moves in a horizontal direction the plate 109 moves vertically. This last named plate travels in metal guides 109^a, which are secured upon posts 110, the said plate being secured to chains 111, which pass over 45 sprocket wheels 112 secured to the shaft 113, the latter operating in bearings 114. The chains 111 are driven by sprocket wheels 115, which are secured to a shaft 116, which operates in bearings 117 mounted upon the base 50 of the cabinet. The shaft 116 is driven by beveled gear 118, which is in turn driven by beveled gear 119 secured to one end of a shaft 120. This shaft is supported in bearings 121 and is driven by a bevel gear 122, the latter engaging the beveled pinion 146 which is loose on the shaft 85 and bevel pinion 151 fast on said shaft. The hub of the gear 84 is engaged by one end of a lever 144, which is pivotally mounted as shown at 145. 55 The opposite end of this lever engages a cam groove 143^a, provided, in a collar 143 mounted upon a shaft 141. This cam is illustrated in Figure 29 of the drawings. The shaft 141 carries a gear 140, which engages 60 the pinion 138 mounted upon the shaft 137,

which also carries a gear 136, which gear is driven from the pinion 135 of the main drive shaft 28.

The operating knob 25, is mounted upon one end of the rod 123, the latter being pivotally mounted as indicated at 124, to one end of a lever 125. This lever is mounted upon a pivot 126 carried by the frame and to the opposite end of the said lever there is pivotally secured one end of a connecting rod 127. The opposite end of this rod is connected to one arm of the bell crank 128 the other arm of the bell crank having secured thereto one end of the connecting rod 129, which is in turn connected to a lever 130 secured upon the shaft 131. This shaft is supported in bearings 132 and has mounted thereon a shifting finger 133, which engages a groove in the sleeve 134 having a clutch at one end thereof. This sleeve is slidably mounted upon the main drive shaft 28, with which it rotates and when the said sleeve engages the toothed hub of a pinion 135, which is loose on the shaft 28 it will drive the said pinion to operate the gear 136. 90

After the indicator has been properly set for the information sheet or curtain required the knob 25 is pressed downward so as to shift the clutch 134 through the shaft 131 and the finger 133 just described. This will cause the clutch 134 to rotate the gear 135 upon the main drive shaft 28 and operate the gear 136 and the gear 140. This will operate the cam 143, which shifts the lever 144, forcing the gear 84 to the right of Figure 6 of the drawings so as to engage the hub of the bevel pinion 146, this rotates the gear 122 in one direction, causing the carrier plate 109 to descend and return the information sheet previously selected. After 100 delivering the sheet, the plate 109 strikes a locking bar 147, which has one end pivoted to the end of the shaft 96 and the other end held by a spring 148. This locking bar is provided with teeth or projections 147^a that fit into the gear 149 secured to the shaft 102. When the locking bar 147 releases the gear 149, the shaft 102 will be revolved by the tension of the gear spring 98 to bring the desired roll into position so that the rod carried by the roll may be engaged by the hooks of the plate 109. The lever 144 will then have been operated to move the gear 84 to neutral position. The said lever is then shifted from the cam to opposite or left side of the clutch and engaged with the clutch member 150, which is secured to the shaft 85. This shaft has secured thereon a beveled pinion 151 which meshes with the gear 122 and operates the latter in a reverse direction and causes the carrier plate 109 to ascend and carry the information sheet or curtain to a position over the display opening 19. When the carrier plate 109 ascends, the bar 147 engages the gear 149 and holds 110

the information mechanism in position. When at its highest point, the bar 109 is yieldingly held by a spring clip 203 or other desired means and the gear 84 is moved to a neutral position. Mounted upon the shaft 131 is a pawl 152, which is engaged by a lever 153, supported upon a pin 154, the lever 153 being held in position by a spring 155. A pin 156 carried by the lever 153, is engaged by a pin 156^a secured to the gear 140. This releases the pawl 152 and throws the clutch 134 in neutral position and stops the information mechanism. On the connecting rod 127, is a collar 158, having a pin 158^a, the latter fitting into one arm of the bell crank 159. The other arm of the bell crank engages a locking bar 160 pivoted at one end to the frame as at 161, the said bar having a spring 162 secured at its other end. This locking bar has teeth 160^a, which fit into the gear 163 on the shaft 87, thereby holding the hand wheel 24 with its pointer locked as long as the mechanism of the information sheets or curtains is in operation.

Located within the upper end of the cabinet, is a source of light, preferably in the form of an incandescent lamp 205. This lamp, is connected with any suitable source of electric current and is included in a circuit, in which there is also included a pair of stationary contacts 206. One of these stationary contacts is located at each end of the display opening 20 and is adapted to be engaged by a movable contact 207, which is carried by each of the levers 79 which operate the ratchet for moving the advertising rolls step by step. It will be thus seen that when the carrying plate 53 engages the end 40 of the lever 79 at the end of its travel, the said lever will close the contacts 206 and 207 at that end of the cabinet and light the lamp 205, which will remain lighted during the pause of the advertising sheet or curtain. Upon the return movement of the plate 53, the contacts will be broken and the lamp extinguished, remaining in such condition until the circuit is closed by contacts 206 and 207 upon the opposite side of the cabinet. Thus, an intermittent lighting and extinguishing of the lamp 205 is effected.

It is believed that when the foregoing description is read in connection with the accompanying drawings, the construction, operation and advantages of the invention will be apparent. The right is herein reserved to make such changes as properly fall within the scope of the appended claims.

In the operation of the invention, the motor 26 supplies power for the operation of the mechanism, the advertising mechanism being operated thereby to bring one of the display curtains before the glass panel 20 and permit it to pause or tarry for

an appreciable period before moving it away and substituting another curtain, after the manner previously explained.

The information mechanism is normally stationary, the clutch 134 which controls the operation of said mechanism being in neutral position. Operation of the knob 25 however, will shift this clutch so as to receive power from the motor and as the indicator has been previously set, the mechanism will be operated to bring the desired sheet into display position in the manner before stated.

Having thus described my invention what I claim as new is:—

1. A machine embodying a cabinet having a display opening therein, a plurality of spring controlled normally rolled curtains, oppositely movable rotatable means for consecutively moving the curtains into position at the end of the display opening, and means engageable with the curtain so positioned to present the same within the opening in unrolled position.

2. A machine embodying a cabinet having a display opening therein, a plurality of spring controlled normally rolled curtains, means for consecutively moving the curtains into position at the end of the display opening and automatically operated means including spaced reciprocating chains engageable with the curtains so positioned to present the same within the opening in unrolled position.

3. A machine embodying a cabinet, having a display opening therein, automatically operated curtain carrying mechanism located at opposite ends of the opening, spring controlled normally rolled curtains carried by said mechanism, and automatically operated curtain engaging members movable backward and forward across said opening, means for operating the curtain carrying mechanism to bring one of the curtains into position at each of the openings in the path of movement of the curtain engaging member, and means for releasing the curtain.

4. A machine embodying a cabinet having a display opening therein, spaced curtain carrying chains located at opposite ends of said opening, spring controlled normally rolled curtains carried by said chains, an automatically operated curtain engaging member mounted for reciprocation across said opening, means operated by the curtain engaging member to bring a curtain into position for engagement by said member and means for releasing the curtain at each end of the stroke.

5. A machine embodying a cabinet having a display opening therein, spaced curtain carrying chains located at opposite ends of said opening, spring controlled normally rolled curtains carried by said chains, an automatically operated plate movable across

6
said opening, means carried by said plate for engagement with a curtain at each end of movement of said plate to display the curtain and means whereby the curtain will be released after such display.

6. A machine embodying a cabinet having a display opening therein, spaced curtain carrying chains located at opposite ends of said openings, spring controlled normally rolled curtains carried by said chains, an automatically operated plate movable across said openings, a rod carried by each curtain and hooks carried by the plate for engagement with the rod to display the curtain before the opening and release the same after such display.

7. A machine embodying a cabinet having a display opening therein, spaced curtain carrying chains located at the opposite ends of said opening, spring controlled normally rolled curtains carried by said chain, an automatically operated plate movable across said openings, a rod carried by each curtain and cam controlled means for moving the plate automatically backward and forward across the opening and means carried by the plate for engaging and releasing a curtain at each end of the stroke.

8. A machine embodying a cabinet having a display opening therein, a plurality of spring controlled normally rolled curtains, means for consecutively moving the curtains into position at the end of the display opening, means engageable with the curtain so positioned to present the same within the display opening in unrolled position, means whereby the curtain will be held in display position for a predetermined period and means controlled by the curtain moving means for illuminating the curtain during such period.

9. A machine embodying a cabinet having a display opening therein, vertically movable rotatable members located in the cabinet below the opening, a plurality of display sheets mounted in said members, vertically movable means engageable with one of the sheets to position the same over said opening, means for selectively positioning the sheet to be engaged, normally inactive operating mechanism, means whereby said mechanism may be released to position the sheet selected in the path of the engaging means and across the display opening, and means including a spring pressed gear engaged locking lever located in the path of the sheet engaging means, whereby the displayed sheet will remain in position until the next operation of the machine.

10. A machine embodying a cabinet having a display opening therein, a rotatable member disposed below the opening, a plurality of display sheets having one end secured to said member, a vertically movable

bar located adjacent the rotatable member, hooks carried by the vertically movable bar for engagement with the opposite end of the sheet, means for operating the rotatable member to selectively position the sheet to be engaged in the path of the hooks, whereby the engaged end of said sheet may be elevated to place the latter over the display opening and means whereby the displayed sheet will remain in position until the next operation of the machine.

11. A machine embodying a cabinet having a display opening therein, spaced conveyor chains located below the opening, a plurality of display sheets, said sheets being normally arranged in roll condition, means carried by the chains for engagement with the sheets, vertically movable means located adjacent the conveyor chains, means carried by the vertically movable means for engagement with one end of the display sheet to disengage said end from the conveyor chains, means for operating the conveyor chains to selectively position the sheet to be engaged, whereby the engaged end of the sheet may be elevated to position said sheet over the display opening and means whereby the displayed sheet will remain in position until the next operation of the machine.

12. A machine embodying a cabinet having a display opening therein, a plurality of spring controlled normally rolled curtains, spaced endless curtain carrying chains arranged in pairs for moving the curtains into position at the ends of the display opening, means for operating the chains in opposite directions to consecutively move the curtains into position and means engageable with the curtains so positioned, to present the same within the opening in unrolled condition.

13. A machine embodying a cabinet having a display opening therein, a plurality of spring controlled normally rolled curtains, spaced endless curtain carrying chains arranged in pairs for moving the curtains into position at each end of the display opening, means engageable with the curtains so positioned to present the same within the opening in unrolled position and means controlled by the last mentioned means for intermittently operating the curtain carrying chains.

14. A machine embodying a cabinet having a display opening therein, a plurality of spring controlled normally rolled curtains, spaced endless curtain carrying chains arranged in pairs for moving the curtains into position at each end of the display opening, means engageable with the curtains so positioned to present the same within the opening in unrolled position, a pivotally mounted lever located at each end of the opening, a ratchet mechanism

operated thereby and means operable with the curtain engaging means for operating the levers to actuate the ratchet mechanism and intermittently operate the curtain carrying chains.

15. A machine embodying a cabinet having a display opening therein, automatically operated curtain carrying mechanism located at opposite ends of the opening, 10 spring controlled normally rolled curtains carried by said mechanism, an automatically operated curtain engaging member movable

backward and forward across the display opening, means operated by the curtain engaging member for intermittently operating 15 the curtain carrying mechanism to bring a curtain into position at each end of the opening in the path of movement of said curtain engaging member and means included in the intermittently operated curtain carrying mechanism for releasing the curtain at each end of the stroke.

In testimony whereof I affix my signature.
JOHN W. DUVAL.
